UNITED STATES PATENT OFFICE.

CHARLES M. BURGESS, OF NEW BRITAIN, AND ROLLIN SANFORD, OF NEW-
INGTON, ASSIGNORS TO RUSSELL & ERWIN MANUFACTURING COMPANY,
OF NEW BRITAIN, CONNECTICUT.

FASTENING FOR MEETING-RAILS OF SASHES.

SPECIFICATION forming part of Letters Patent No. 234,387, dated November 16, 1880.

Application filed September 16, 1880. (No model.)

To all whom it may concern:

Be it known that we, CHARLES M. BURGESS, of New Britain, and ROLLIN SANFORD, of Newington, both in the county of Hartford and 5 State of Connecticut, have invented certain new and useful Improvements in Fasteners for Meeting-Rails of Sashes, of which the following is a specification.

Our invention relates to improvements in 10 fasteners for the meeting-rails of sashes in which the sweep bears a flanged post and eccentric bearing at its inner end and is pivoted in place in a box or case by means of two springs and a sliding bolt; and the objects of 15 our improvements are to lessen the cost of construction and to afford greater security. We attain these objects by the mechanism illustrated in the accompanying drawings, in which—

20 Figures 1 and 2 are plan views; Fig. 3, a vertical section on line $x x$ of Fig. 2. Fig. 4 is an under-side view of one part. Fig. 5 is a plan view of one plate. Fig. 6 is a plan view of the sliding bolt, and Fig. 7 is a side elevation of the sweep.

A designates an elevated plate or box 25 designed to be secured to the lower rail of the upper sash. Said box is open or hollow on the under side, and is of sufficient depth to receive springs for bearing upon and holding the sweep in the box, substantially like sash-fasteners now in common use. This box differs from prior ones in the fact that it is provided upon its upper side with a transverse 30 recess, a , for the reception of a flat and thin sliding bolt, b . This recess a is of such depth as to extend into the hollow inside of the box and leave an opening through the top of the box, the bolt b resting at each end upon the 35 edges or sides of the box, the rear edge being left of such thickness that the rear end of the bolt b will not be carried beyond it when thrown to its extreme forward position. The sliding bolt b is fitted to the recess in the box 40 A, and is provided with a circular opening or hole, c , which fits and receives an eccentric bearing upon the sweep B. The cam-shaped keeper C is the same as those in common use, except that it is recessed upon its upper side

for a short distance inward from the straight 50 side, which confronts the box A, for the purpose of receiving the end of the bolt b .

The sweep B is cast in any desired design, with the ordinary downwardly-projecting lug d , for engaging the cam-edge of the keeper C. 55 The opposite end of the sweep has the bearing e for the bolt, the squared post m , against which the springs $n n$ act, and the flange o , for taking over the under edges of the spring. The several parts of the sweep may be, and 60 preferably are, cast in one and the same piece, and the bearing e is eccentric to the axis of the squared post m .

In order to assemble the parts the flange o and post m are passed through the hole c in 65 the bolt b , and the bearing e of the sweep is received in the bolt. The bolt, with the sweep in it, is then placed in the recess a , and the springs $n n$ are inserted to hold the whole in place. The bearing on the sweep, which fits 70 the hole in the bolt b , governs the sweep axially, so as to prevent its axis from moving either to the right or left, while its axial position, from front to rear, is governed entirely by the squared post m and springs $n n$. Small 75 lugs s are cast upon the under side of the bolt b to limit the extent of its forward movement.

In Fig. 1 the parts are represented with the sweep thrown to the right and the sash unlocked, while in Figs. 2 and 3 they are represented with the sweep brought to the front and the sash locked. Moving the sweep from either side to the front to draw the sash-rails together also operates to throw the bolt outward, with its front end over the keeper, as 85 shown in Figs. 2 and 3, when the bolt performs the double function of firmly locking the sash and of cutting off all access to the sweep by means of a knife-blade or other thin instrument inserted between the sash-rails 90 from the outside.

We are aware that sweeps in prior sash-fasteners have been provided with a flanged post, and were held in place by a spring or springs within a box or case which bore upon 95 the square of the flanged post; also, that a prior patent shows a sash-fastener having a sweep pivoted within a box upon a fixed axis

and with a slotted and sliding bolt under the sweep at the base of the box, which bolt was thrown forward over the keeper by means of a pin on the sweep, which entered a slot in the bolt. Both of said prior constructions are hereby disclaimed.

We claim as our invention—

The combination of the sweep having the lug *d* at its outer end, the eccentric bearing *e*,

and flanged post *m* at its inner end, the springs *n*, bolt *b*, box *A*, and keeper *C*, substantially as described, and for the purpose specified.

CHARLES M. BURGESS.
ROLLIN SANFORD.
